BOTTLE

John Slavin, South Orange, N. J., assignor to Barton Distilling Company, Chicago, Ill., a corporation of Delaware

Application June 15, 1953, Serial No. 25,480

Term of patent 14 years

(Cl. D58—6)

To all whom it may concern:

Be it known that I, John Slavin, a citizen of the United States, residing at South Orange, in the county of Essex and State of New Jersey, have invented a new, original, and ornamental Design for a Bottle, of which the following is a specification, reference being had to the accompanying drawing, forming part thereof.

In the drawing

Fig. 1 is a front elevational view of a bottle, showing my new design;

The characteristic feature of my design for the bottle shown resides in the irregular, wavy surface ornamentation shown.

I claim:

The ornamental design for a bottle, substantially as shown and described.
